FIG. 18 is a right, rear, top perspective view of the invention illustrated in FIG. 17;
 FIG. 19 is a front view of the invention illustrated in FIG. 17;
 FIG. 20 is a rear view of the invention illustrated in FIG. 17;
 FIG. 21 is a right side view of the invention illustrated in FIG. 17;
 FIG. 22 is a left side view of the invention illustrated in FIG. 17;
 FIG. 23 is a top view of the invention illustrated in FIG. 17;
 FIG. 24 is a bottom view of the invention illustrated in FIG. 17;
 FIG. 25 is a top, right, front perspective view of a protective case showing a fourth embodiment of the new design;
 FIG. 26 is a right, rear, top perspective view of the invention illustrated in FIG. 25;
 FIG. 27 is a front view of the invention illustrated in FIG. 25;
 FIG. 28 is a rear view of the invention illustrated in FIG. 25;
 FIG. 29 is a right side view of the invention illustrated in FIG. 25;
 FIG. 30 is a left side view of the invention illustrated in FIG. 25;
 FIG. 31 is a top view of the invention illustrated in FIG. 25;
 FIG. 32 is a bottom view of the invention illustrated in FIG. 25;
 FIG. 33 is a top, right, front perspective view of a protective case showing a fifth embodiment of the new design;
 FIG. 34 is a right, rear, top perspective view of the invention illustrated in FIG. 33;
 FIG. 35 is a front view of the invention illustrated in FIG. 33;
 FIG. 36 is a rear view of the invention illustrated in FIG. 33;
 FIG. 37 is a right side view of the invention illustrated in FIG. 33;
 FIG. 38 is a left side view of the invention illustrated in FIG. 33;
 FIG. 39 is a top view of the invention illustrated in FIG. 33; and,
 FIG. 40 is a bottom view of the invention illustrated in FIG. 33.
 The broken lines in the drawings depict portions protective case that form no part of the claimed design. The parallel

diagonal shading lines on the protective case in the embodiments of FIGS. 1-8 indicate translucency.
